UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF PENNSYLVANIA.

BOILER-FLUE-CLEANER SYSTEM.

1,148,846.

Specification of Letters Patent.

Patented Aug. 3, 1915.

Application filed March 8, 1915. Serial No. 12,792.

To all whom it may concern:

Be it known that I, FREDERICK W. LINAKER, subject of the King of England, residing at Dubois, in the county of Clearfield 5 and State of Pennsylvania, have invented certain new and useful Improvements in Boiler-Flue-Cleaner Systems, of which the following is a specification.

This invention relates to boiler flue cleaner systems, of the type employing a fluid-distributing pipe having a nozzle or nozzles or outlet or outlets for projecting a jet or jets or stream or streams of cleaning fluid among the tubes of a boiler to remove 10 soot therefrom, the jet or jets or stream or streams of fluid being directed along radial lines or paths to adapt it to cover a great tube-surface area, and to project the cleaning fluid in planes parallel or approximately 15 parallel with the inclined or obliquely arranged tubes.

The present invention is especially designed for use in connection with boilers of the Stirling type, in which banks of parallel 20 inclined boiler tubes are employed and so disposed within the boiler setting as to present inclined tube surfaces to the action of the cleaning fluid, though is not confined in its adaptation to this specific form of boiler, 25 but involves certain important features as will later appear adaptable to flue cleaners for various types of boilers.

A serious obstacle heretofore, to the successful adaptation of boiler-tube cleaner systems to boilers of the Stirling type has been the liability of "burning out" of the fluid-distributing pipe or pipes, which are exposed to the direct heat of the fire-box, and the present invention has for one of its main 30 objects the avoidance of this difficulty by so locating the fluid-distributing pipe or pipes with relation to the fire chamber and the baffles and inclined boiler tubes, as to remove 35 said distributing pipe from the destructive heat zone that would soon destroy the effectiveness of the cleaner system, by burning out the fluid distributing pipe or pipes.

A further object of the invention is to provide a fluid-distributing pipe of a boiler tube cleaner system with discharge pipes or nozzles, the fluid-distributing pipe being capable of rotation upon pivotal supports to

remove the discharge nozzles when not in use out of the line of fire draft, to prevent heating of same, and thus to keep down their temperature and reduce to a minimum 55 their exposure to destructive heat.

A further important object of the present invention is to provide in a flue cleaner, discharge nozzles carried by the fluid distributing pipe so arranged as to provide for a discharge of cleaning fluid in streams at right angles to the longitudinal axis of the distributing pipe and also in streams on lines oblique to the longitudinal axis of the 60 distributing pipe whereby to materially increase the area of tube or other boiler surface that may be cleansed by each discharge nozzle.

With these objects in view, the invention 70 consists of the combination with a bank of boiler tubes, of a fluid-distributing pipe so located with respect to said tubes, and the baffle plates and bridge-wall of a boiler installation as to be out of the destructive heat 75 zone of the boiler.

The invention also comprehends further novel features hereinafter described and set forth in the appended claims.

In the accompanying drawing which constitutes a part of this specification: Figure 1 is a vertical sectional view of a boiler of the Stirling type with my invention applied thereto. Fig. 2 is a fragmentary longitudinal sectional view taken through the boiler 80 setting, showing the fluid distributing pipe in rear elevation, the boiler tubes being broken away. Fig. 3 is an enlarged detail view in vertical section of a portion of a Stirling boiler, showing one of the nozzles of 85 the distributing pipe in its extreme "fluid-discharging" position in full lines, and in dotted lines showing the "rest" or "protected" position of the nozzles. Fig. 4 is a rear elevation of the same. Fig. 5 is a perspective view of one form of hanger or support for the distributing pipe showing a part of the pipe, and a nozzle in dotted lines, and, Fig. 6 is a similar view of another form 90 of support for the distributing pipe, a portion of the latter being shown in dotted lines.

In boilers of the Stirling type, where there are banks of tubes as A, B and C, with

the bank A directly subjected to the extreme heat of the furnace, considerable difficulty has been experienced in cleansing the tubes of such bank A, particularly the upper portion thereof, due to the fact that a fluid distributing pipe located in the path of the natural draft of the furnace is liable to rapid deterioration.

In the present invention, the distributing pipe is so located, as to be protected from the direct heat of the furnace chamber, and the nozzles of said pipe are of a form to be projected beyond the edge of the pipe protecting baffle to effectually cleanse the upper portion of the boiler tubes as well as the connecting tubes between the drums at the top of the boiler.

In boilers of the type referred to, the same are constructed with an inclined baffle 10 extending transversely of the boiler, directly above or to the rear of the bank of tubes A so that the heat from the furnace F will be required to pass up the bank A before reaching banks B and C. This inclined baffle is generally provided near its upper end with an upwardly-projecting ledge or guard 11 extending throughout the length of the baffle and projecting transversely into the space between the banks A and B. In this invention, I utilize this provided baffle and its ledge to shield the fluid distributing pipe and its nozzles from the heat of the furnace when they are not in use. To this end, I locate, transversely of the boiler, near the upper end of the baffle 10, a fluid distributing pipe 12 suitably mounted and adapted for rotation whereby the nozzles carried thereby may be projected over the upper edge of the baffle, and when not in use turned into position back of said baffle. This pipe may be rotated in any suitable manner, as by a sprocket wheel 14 on the outer end of the pipe, engaged by a chain 15, it being understood that adjacent the wheel 14 or other form of operating device is a swivel or packed joint, such for instance, as shown in Eichelberger Patent 705,912, July 29, 1902, which permits of the distributing pipe being rotated without affecting the feed pipe (not shown) which supplies the distributing pipe with cleansing fluid.

The distributing pipe is here shown as received at its inner end in the boiler setting, and intermediate its ends it is supported by hangers 16 shaped at one end to hook over the upper end of the baffle 10 and curved outwardly and upwardly at their lower ends to form seats or saddles 17 in which the pipe 12 is received. That strain may be relieved from the upper end of the baffle, I also employ supporting brackets for the distributing pipe (see Fig. 6) consisting of a supporting rod or stem 18 socketed at its lower end in a base plate 19 that rests on

the ledge 11, the rod or stem 18 at its upper end having a sleeve or equivalent carrier 20 for the pipe 12. Both of these pipe supports may be used as here shown, or either of them, or any equivalent support, as I do not limit myself to any specific manner of supporting the pipe.

To effect a desired projection of the cleansing fluid from the distributing pipe 12, a nozzle is employed which can be projected beyond the upper end of the baffle. The pipe is provided with as many of these nozzles as may be desired, and each consists of an elongated hollow stem or pipe section 21 connected at its inner end to the pipe 12, and of a length to extend beyond the baffle 10, the outer end of the stem being curved back so that the discharge end of the nozzle is on a plane parallel to the body or straight portion of the stem. Onto this discharge end of the stem, I preferably secure a nozzle member 22 here shown as provided with a plurality of discharge ports, one discharging straight in line with the discharge of the stem and the other at an oblique angle thereto. While the nozzle may consist only of the stem having the curved discharge end, it is desirable and preferable to use therewith the nozzle member having a plurality of discharge ports, as this construction provides for a wide sweep of the cleaning fluid during operation, the movement of the nozzle members from the "rest" position of the nozzles describing such an arc as to project the cleansing fluid onto the connecting pipes 23 between drums D, D', and also onto the extreme upper portion of tubes in bank A where they connect with drum D', and as the nozzles reach the full line position shown in Figs. 1 and 3, the cleaning fluid is projected both obliquely across the tubes and straight down along the tubes as shown in Fig. 3 so as to most effectually cleanse the tubes.

When not in use, the distributing pipe is rotated so as to turn the nozzles back behind the baffle 10 where they are fully protected from the high degree of heat from the fire chamber that obtains in this portion of a boiler of the type shown and described. When the hanger form of support 16 is employed, the saddle or seat 17 thereof is provided with a slot 17' that receives the stem of the nozzle and acts as a guide for the nozzle stems insuring the centering of the curved ends of the nozzles between the tubes of the boiler.

The location and distribution of the distributing pipe as shown and described and the providing of same with curved jets or nozzles, enables me to project jets or streams of cleansing fluid in paths at substantially right angles to the axis of the distributing pipe, rendering it possible to apply parallel directed streams of cleaning fluid from a

distributing pipe to portions of the tubes of a Stirling boiler it has heretofore been extremely difficult to readily cleanse, and by employing multiple discharge orifices for the jets or nozzles, I am enabled to maintain the cleaning action during the entire movement of the nozzles from their "rest" or normally inoperative position. The angle of the nozzles, it will be understood, will be 5 in accordance with the distance of the end of the baffle from the steam drums. When in the "back" or "rest" position, with the cleaning fluid turned on, the straight-line discharge port of the nozzle member cleans 10 off the drum D and water tubes 23 and as the pipe is swung around the bottom of drum D' and upper portions of the bank of tubes are cleansed, the cleansing action down along the tubes of bank A continuing 15 as the nozzles reach the limit of their throw toward the bank A of tubes.

What I claim as new is:—

1. In a boiler flue cleaner system, the combination with an inclined baffle and a bank 25 of inclined boiler tubes, of a fluid distributing pipe adapted to discharge cleaning fluid in streams within the spaces between said tubes, said pipe being transversely disposed within the boiler setting back of said baffle 30 out of the destructive heat zone of the fire chamber of said boiler, curved nozzles projecting from said pipe and adapted to be projected over the edge of said baffle, and means for rotating said pipe to project said 35 nozzles beyond the baffle and for returning the nozzles to rest position in back of the baffle.

2. In a boiler flue cleaner system, the combination with an inclined baffle and a bank 40 of inclined boiler tubes, of a fluid distributing pipe adapted to discharge cleaning fluid in streams within the spaces between said tubes, said pipe being transversely disposed within the boiler-setting back of said baffle 45 out of the destructive heat zone of the fire chamber of the boiler, curved nozzles carried by said pipe adapted when projected beyond the baffle to discharge fluid between said flues, and means for rotating said pipe 50 to turn its nozzles to a position where they are protected by said baffle from the heat of the fire chamber of said boiler.

3. In a boiler flue cleaner system, the combination with an inclined baffle and a bank 55 of inclined boiler tubes, of a fluid distributing pipe adapted to discharge cleaning fluid in streams within the spaces between said tubes, said pipe being transversely-disposed within the boiler setting back of said baffle 60 out of the destructive heat zone of the fire chamber of said boiler, supporting-means for said pipe permitting its rotation, curved nozzles projecting from said pipe and adapted to have their discharge ends projected 65 over the edge of said baffle, and means for

rotating the pipe to project said nozzles beyond the baffle and for returning the nozzles to rest position in back of the baffle.

4. In a boiler flue cleaner system, the combination with a bank of inclined boiler tubes, of a rotatable fluid distributing pipe adapted to discharge cleaning fluid in streams within the spaces between said tubes, said pipe being disposed transversely of said bank of tubes, curved nozzles carried by 70 said pipe each provided with two-way discharge nozzle-members, one of the discharge orifices of each nozzle member being at right angles to the longitudinal axis of the distributing pipe, and the other discharge 75 orifice being at an oblique angle to the longitudinal axis of the distributing pipe, and means for rotating said pipe.

5. In a boiler flue cleaner system, the combination with a bank of inclined boiler tubes, of a rotatable fluid distributing pipe mounted adjacent said bank of tubes transversely thereto, two-way nozzles carried by 80 said pipe, one of the discharge orifices of said nozzle being disposed to project cleaning fluid at right angles to the longitudinal axis of the distributing pipe and the other discharge orifice disposed to discharge cleaning fluid at an oblique angle to the longitudinal axis of the distributing pipe, and 85 means for rotating said pipe.

6. In a boiler flue cleaner system, the combination with a bank of inclined boiler tubes and an inclined baffle back of said tubes, of a fluid distributing pipe located back of 90 the baffle and below the upper end thereof, and curved nozzles carried by said pipe of a length to overhang the upper end of the baffle to discharge cleaning fluid down along the bank of tubes in front of the 95 baffle.

7. In a boiler flue cleaner system, the combination with a bank of inclined boiler tubes and an inclined baffle back of said tubes, of a rotatable fluid distributing pipe 100 located back of the baffle just below the upper end thereof, and curved nozzles carried by said pipe projecting over the upper end of said baffle, said nozzles having two discharge orifices, one orifice disposed to 105 project cleaning fluid in streams at right angles to the longitudinal axis of the distributing pipe and the other orifice disposed to project the cleaning fluid in streams oblique to the longitudinal axis of the distributing pipe.

8. In a boiler flue cleaner system, the combination with the boiler tubes to be cleaned, of a rotatable fluid distributing pipe arranged transversely of the tubes and adapted to project cleaning fluid between the spaces of said tubes, and two-way nozzles carried by said distributing pipe each having one discharge orifice disposed to discharge cleaning fluid in streams at right an- 115 120 125 130

gles to the longitudinal axis of the distributing pipe and the other discharge orifice disposed to discharge the cleaning fluid in streams oblique to the longitudinal axis of said distributing pipe.

9. In a boiler flue cleaner system, the combination with an inclined bank of boiler tubes, and an inclined baffle, of a fluid distributing pipe rotatably-mounted back of 10 the baffle, supporting means for said pipe engaging the baffle, and curved nozzles car-

ried by the pipe of a length to have their discharge ends project over the baffle to discharge cleaning fluid onto the tubes, and means for operating said pipe to project 15 and withdraw the nozzles.

In testimony whereof I affix my signature in presence of two witnesses.

FREDERICK W. LINAKER.
